UNITED STATES PATENT OFFICE

167,037

SEPARABLE BROOCH

Adolph Katz, Providence, R. I., assignor to Coro,
Inc., New York, N. Y., a corporation of New York

Application February 18, 1952, Serial No. 18,568

Term of patent 7 years

(Cl. D45—19)

To all whom it may concern:

Be it known that I, Adolph Katz, a citizen of the United States of America, residing in Providence, county of Providence, and State of Rhode Island, have invented a new, original, and ornamental Design for a Separable Brooch, of which the following is a specification, reference being had to the accompanying drawing, forming part thereof.

Fig. 1 is a plan view of a separable brooch showing my new design.

Fig. 2 is an edge view thereof, and

Fig. 3 is a plan view illustrating the brooch in separate positions.

I claim:

The ornamental design for a separable brooch, substantially as shown and described.

ADOLPH KATZ.
